UNITED STATES PATENT OFFICE.

CHARLES S. BATDORF, OF BROOKLYN, NEW YORK, ASSIGNOR TO AUTOMATIC COIN-WRAPPING MACHINE COMPANY, OF NEW YORK, N. Y., A CORPORATION OF NEW YORK.

COIN-PACKAGE-SEALING DEVICE.

1,168,462.

Specification of Letters Patent.

Patented Jan. 18, 1916.

Application filed April 25, 1912. Serial No. 693,133.

To all whom it may concern:

Be it known that I, CHARLES S. BATDORF, a citizen of the United States, and resident of Brooklyn, in the county of Kings, State 5 of New York, have invented a new and useful Improvement in Coin-Package-Sealing Devices; and I hereby claim the following to be a full, clear, and exact description thereof.

My invention relates to coin or article 10 package sealing devices particularly, though not exclusively, adapted for sealing packages of coin of different denominations.

The invention is particularly concerned 15 with means for turning in or crimping the ends of the paper wrapper within which the coins or articles are inclosed.

The invention has for its object the provision of means whereby after the coins have been inclosed within the paper wrapper 20 or wrapper tube in any manner, either by hand or by a package machine, such as illustrated in my co-pending application, Serial No. 727,219, filed on the 22d day of October, 1912, the ends of the wrapper or 25 wrapping tube may be turned in or crimped to thus seal the coins or articles within the wrapper.

The invention has further for its object 30 to provide an extremely simple and compact device adapted to wrap all sizes or denominations of coin, and one which may be economically manufactured.

In devices of this character as heretofore constructed and as illustrated for example in 35 my Patent No. 998,834, dated July 25, 1911, the package sealing or crimping members are held stationary while the package is revolved rapidly to enable the crimping members to effect the crimping or sealing 40 operation. This mode of procedure necessitates the use of a machine or apparatus of some kind to rotate the package and also hold the wrapper securely around the coins or articles while the package is being so 45 rotated.

In order to dispense with the necessity of a machine for holding and rotating the package, and in order to simplify greatly the operation of sealing or crimping and 50 furthermore to provide simple but efficient means for sealing or crimping a package which may be formed entirely by hand or by a very simple form of package apparatus, I have devised a rotatable package sealing 55 or crimping member to which the ends of

the article inclosing wrapper may be presented and by which they may be readily and quickly crimped even when the package is simply held in the hand of the operator, or it may be in some simple form of holder, such as that illustrated in my co-pending application Serial No. 702,150, filed on the 7th day of June, 1912. In this way I dispense with the necessity of the complicated mechanism for packaging the coin in its wrapper to prepare it for the crimping operation, and also dispense with wrapping rolls by which the coins may be wrapped and the wrapper held thereon during the crimping operation, and finally dispense 60 with the more or less complicated mechanism for advancing the crimpers to progressively turn or crimp the edge of the package while the latter is so held by the rolls, all as illustrated for example in my Patent 65 No. 998,834, above referred to. This simplified mode of procedure has the special advantage that coin in small quantities may be packaged and sealed as perfectly and effectively as the operation could be performed on a machine of my patent, thus placing the means in the hands of small 70 banks or institutions which handle small quantities of coin, for effectively packaging coin without incurring the expense of acquiring one of these more or less elaborate 75 machines.

In short my invention presents in its simplest form a device for sealing a coin or article package by the turning in or 80 crimping of the end of the wrapper irrespective of the means by which the package is held and presented to the sealing member *per se*.

With these objects in view the invention 85 consists in a construction and arrangement of parts, a preferred embodiment of which is illustrated in the accompanying drawings, in which—

Figure 1 is an end view of the wrapper 100 sealing, inturning, or crimping member. Fig. 2 is a side elevation of said member detached from its motor shaft. Fig. 3 is a longitudinal sectional view of said member showing the crimpler finger and means for 105 fastening same, in elevation. Fig. 4 illustrates a convenient means for forming the wrapper into a tube to receive the coin. Fig. 5 is a view of a completed package showing the sealed inturned or crimped ends 110

thereof in section. Fig. 6 is a diagrammatic view illustrating the intermediate steps which take place in the crimping operation. Fig. 7 is a view similar to Fig. 6 showing the crimping operation carried to completion; and Fig. 8 is a view of an apparatus adapted to seal or crimp both ends of the package in the same operation.

While for convenience I employ the terms "crimper" and "crimping" in the following description, it is to be understood that I do not intend to limit myself to any particular arrangement or disposition of the inturned ends of the wrapper inasmuch as it is usually found in practice that said ends are not usually crimped in the common acceptation of that term, but are inturned or infolded. I therefore use the term "crimp" in a sense broad enough to cover any arrangement of the ends of the wrapper by which they may afford an effective seal to the package and effectively retain the coins therein.

In the embodiment of my invention herein selected for illustration, and as shown in Figs. 1 to 3 inclusive, the crimping member comprises preferably a cylindrical body portion 1 having a transverse web 2 at the base thereof from which projects a spindle 3 which may be attached to or integral with the web 2 as desired, the spindle being threaded as at 4 to engage a correspondingly threaded portion of a driving shaft, such for example as the shaft of an ordinary electric motor. At the inner end of the crimper body or cylinder is located the crimping finger 5 having its shank secured in a recess 6 of the body wall preferably by a screw and washer 7, although any desired fastening means may be employed. The working end of the crimping finger is turned over as at 7 (Fig. 1) to embrace the projecting end 8 of the wrapper (Fig. 4) which extends beyond the coin about the same distance as it is beyond the end of the mandrel 9, as shown in Fig. 4. As seen in Fig. 1, this crimper finger extends somewhat tangentially of the opening of the package receiving opening in the body portion and the crimper device in operation is rotated to the left as viewed in Fig. 1, so that this tangential arrangement serves to cause the finger to smoothly and easily engage the end portion of the wrapper to turn the same in. It will be noticed that the space between the extreme turned in end 7 of the crimper finger, to the side wall of the package receiving opening is such as to readily receive the several thicknesses of the wrapper when coiled about the coin. The curvature of the finger is sufficiently abrupt to securely and neatly turn over the edge of the wrapper end or turn it in upon itself to form the inturned sealed or crimped end for the package.

While I do not confine myself to a device

for sealing, turning in or crimping the end of the wrapper in a special and specific manner, I have illustrated in Figs. 6 and 7 the several positions which the inturned wrapper end usually takes during the crimping operation, which furthermore illustrate clearly the security of this sealing as well as the positive stop shoulder for the coin within the package. In Fig. 6 the wrapper end 8, as shown in dotted outline, is by the first action of the crimper given one complete fold inward, as indicated at 10 Fig. 6. The next revolutions of the crimper again folds this once folded end in upon itself, as indicated at 11 Fig. 7.

The diagrammatic views Figs. 6 and 7 are of course somewhat exaggerated for illustration, but it has been found in practice that the inturned ends take substantially the form therein shown. A more exact idea of the actual conditions existing in these inturned ends, is illustrated at 12 Fig. 5. That is to say crimping ends take substantially the bead form there shown rather than the extended form shown in Fig. 7. Nevertheless in practically all cases, it has been found that the double fold illustrated in Fig. 7 takes place. It will be seen, therefore, that this inturned or crimped end affords a most secure and perfect fastening for ends of the package. It will also be seen from the above description that while I speak of the inturned ends as crimped they are not necessarily crimped in the accepted meaning of the term, but are simply inturned. However, the lip at the extreme end of the inturned crimper finger, does, as a matter of fact in both instances, tend to crimp the innermost folds of the wrapper ends.

The term "self sealed" meaning sealed by reason of the position which the material of the wrapper itself is compelled to take, as distinguished from any extraneous means, such as gluing, or employing any other means, is an appropriate broad term to apply to this form of package fastening, and wherever this term "self sealed" is employed herein, it is to be understood in this sense.

In order to prevent the sealing finger 5 from abrading the face of the end coin and also to provide a convenient positioning and alining stop for the package when it is introduced into the crimper, I provide a center stop surface such as a pin 13 (Figs. 1 and 3) adapted to engage the center of the end coin and which with the end of the crimper finger holds the coin package in proper alinement or position for the crimping operation. This stop pin, conveniently so called through the stop surface may be of greater area than here shown, projects beyond the bottom of the wrapper receiving opening of the crimper device; in this case the inner face of the cross bar 2 thereof, to an extent equal to the depth of the crimped

head of the wrapper and it will be noticed also that the inner face of the bend of the crimping finger is substantially flush or in alignment with this bottom surface so that it will be inturned or crimped to the desired extent determined by these factors to effectively seal the package and hold in the coins.

In operating my improved crimping device, a piece of wrapping material of proper length, preferably sufficient length to coil twice about the coins of a given diameter is rolled up on a mandrel 9, which is provided with a convenient handle 9', and which has a shoulder 9² against which the one end of the wrapper abuts and by which the edges of the different coils of the wrapper are alined. The wrapper may be of the form indicated in my Patent No. 717,964, dated Jan. 6, 1903, of the form having the end diagonal to the length, but parallel to each other. Again the wrapper may be formed with the rear or inner end straight and the outer end diagonal or pointed. The object of making the outside end diagonal or notched is to cause the end edges of the wrapper to wind spirally about the package and thus snugly hug the same much in the manner of the spirals of a cornucopia around the body thereof.

When the tube is formed, as shown in Fig. 4, it may be filled with the desired number of coins in any preferred manner, by hand or by machine, such as illustrated in my co-pending application, Serial No. 727,219 above referred to. With the tube thus filled, the same may be grasped firmly by hand and the end thereof thrust into the package receiving opening of the revolving crimper member and a gentle pressure exerted against the crimper finger. The crimper finger thereupon first inturns the end as shown in Fig. 6, then turns it in again as illustrated in Fig. 7 and finally beads the inturned end as shown in Fig. 5. The depth of the crimper finger from the curve to its outer end and the depth of the stop pin 13 determining the depth of the bead upon the end of the package. It will be seen, therefore, that with a simple apparatus of this character, perfect packages of coin may be formed either in comparatively large numbers or as small numbers as the quantity of coin requires. The apparatus may be especially advantageous where small quantities of coin are to be handled and where a large coin wrapping machine, such as that illustrated in my patent referred to above could not be used an economical proportion of time.

One advantage of this device which I especially desire to emphasize lies in the fact that the coin may be wrapped in any desired manner, either by hand entirely by placing the wrapper directly about the coins before being formed in a tube as illustrated

in Fig. 4, or after it is formed into a tube in said figure, or after formed into a tube with one end previously crimped or in-turned: The latter operation may be performed by presenting the coin wrapper upon the mandrel, as shown in Fig. 4, to the crimper device and turning in one end before the tube is filled with coin. On the other hand, a tube such as that shown in Fig. 4, may be used and a suitable filling holder such as illustrated in my co-pending application Serial No. 702,150, above referred to, may be used by which the filled tube may first be crimped at one end and then the other by simply presenting one end of the package to the crimper, reversing the package in the holder and presenting the other end.

It will be seen, therefore, that my invention, in the broadest aspect in which it appears to me at present comprises a rotary crimping member adapted to receive and crimp a coin package whether the same is held in the hand of the operator, or in a convenient holder which may be in the hand of the operator, or on a proper rest or support of some sort. In any aspect of the invention, however, it will be noted that the crimper finger revolves while the package may and preferably is, held stationary, or it might be revolved in the opposite direction, and if, for any reason, it may seem desirable, it may be revolved in the same direction as the crimper finger but at less speed. The substantially tangential arrangement of the crimper relative to the body of the crimper member effects what may be termed a drag in the crimping operation to smooth or overlay the end of the wrapper without danger of tearing or abrading the end by acting at too abrupt an angle to the circle of the crimping operation.

In Fig. 8 is illustrated more or less diagrammatically an apparatus by which both ends of the wrapper may be crimped at one and the same time. This apparatus comprises suitable standards 14 and 15 in one of which is journaled a shaft 16 having a pulley 17 to be connected with any suitable source of power and the crimper member 18 such as that above described. The standard 15 has splined therein a shaft 19 upon which is a pulley 20 and a second crimper member 21. An open ended tube of coin may be grasped by the operator at substantially the center, one end introduced into the longitudinal stationary crimping member 18 whereupon the longitudinal crimper member 21 may be applied at the opposite end of the tube, and by exerting slight pressure longitudinally of the shaft 19 by any convenient means, the ends of the package will be crimped as heretofore described.

It is to be noted that the crimpers in this apparatus revolve in opposite directions, so

that there is no tendency of the package to turn in the hand of the operator, and it is simply necessary that the package be firmly held. The crimping or inturning operations in this case are precisely the same as hereinbefore described. To wrap coin or articles of different diameter I simply substitute members of greater or less diameter as required.

10 While I have herein described particular forms of my invention, it is to be understood that the same may be altered in details and in the relative arrangement of parts within the scope of the appended 15 claims.

What I claim is:

1. A coin package sealing device comprising a rotatable cylindrical body portion having a crimpler finger mounted thereon and 20 extending substantially tangentially within said body portion and adapted to inturn the end edges of a coin package wrapper when the same are guided thereto by said body portion.

2. A coin package sealing device comprising a rotatable cylindrical body portion having a crimpler finger at the inner end thereof extending substantially tangentially within said body portion and a stop on said body portion adjacent said crimpler member to 30 determine the depth of the crimped portion of the wrapper.

3. A coin package sealing device comprising a rotatable cylindrical body portion having a crimpler finger at one end thereof extending substantially tangentially into the bore of said body portion and a stop surface in alignment with the end of said crimpler member and adapted in conjunction therewith to position the end of the package and 40 determine the depth of the inturned portion of the wrapper thereof.

In testimony whereof, I the said CHARLES S. BATDORF have hereunto set my hand:

CHARLES S. BATDORF.
